FIG. - 3.

FIG. - 1.

FIG. - 2.

FIG. 1 is a side elevational view of a milk bottle showing my new design, the opposite side being the same in appearance;

FIG. 2 is a top plan view on an enlarged scale; and

FIG. 3 is an elevational view of the neck and finish portions on a still larger scale.

The dominant features of my design reside in the portions shown in full lines.

I claim:

The ornamental design for a milk bottle, as shown and described.
